INSOLE

Mark L. Brown, Vanceburg, Ky., assignor to L. V. Marks & Sons Company, Cincinnati, Ohio, a corporation of Ohio

Application August 5, 1941, Serial No. 405,527

4 Claims. (Cl. 36—43)

This invention relates to shoes and is particularly directed to an improved insole construction. More specifically, the invention is directed to an insole which includes a cushioned forepart adapted to increase the flexibility of the forepart of the shoe construction and to make the sole soft and yielding whereby it will more readily conform to the shape of the foot of the wearer.

In the provision of a sole of this type, it is essential that the pad or cushion part of the insole be firmly attached in position. If the attachment is not secure, the pad or insert will creep or bunch after a certain period of use. The repeated bending or flexing of the forepart of the shoe together with pressure of the foot on the cushion pad normally tends to displace the pad. If the pad is displaced, the shoe becomes quite uncomfortable to the wearer.

It has been an object of the present inventor to provide an insole construction wherein the entire forepart of the insole is constituted by a flexible cushion pad, which pad is joined with the heel and shank portion of the insole in such manner that it will not be displaced.

It is preferable to construct the resilient pad portion of some composition such as cork and latex bonded together. This material, because it is soft and yielding, has a tendency to pull apart. This renders it difficult to attach the pad portion to the sole by means of stitching.

In view of the use of these materials such as cork and latex or like compositions, it has been the further object of the present inventor to reinforce the material in such manner that it may be firmly attached by means of stitching. In other words, an arrangement is provided whereby the stitching cannot tear loose. It is preferable to use a skin or covering sheet of some tough material such as leather or fabric adhesively applied to the upper or lower or both surfaces of the pad.

Another advantage resulting from the use of the covering sheets is that the cushion material cannot spread laterally and its yielding is confined to a vertical direction. It is preferable to use such material as coutil which does not stretch, and the preferred embodiment is to use the material on both the upper and lower sides of the cushion.

The resilient pad is thicker than the heel and shank portion of the insole and through the manner of attachment to the heel and shank portion of the insole along the forward edge thereof, has its thickness evenly distributed relative to the thickness of the body of the insole. A binding

strip may be used in the attachment or connection of the parts.

It has been a further object of the present inventor to provide an insole of this type which may be used either for right or left hand shoes; that is, one which may have either face disposed upwardly.

It has been a still further object of the present inventor to provide an insole construction of the type referred to heretofore which includes a sewing rib or lip element for incorporation of the insole in a welt-type shoe. The arrangement in no way interferes with the flexibility of the forepart of the insole and results in further reinforcement and unity of the fabricated insole.

This application is a continuation in part of my previous application filed January 4, 1940, Serial No. 312,415, and entitled "Insoles."

Other objects and certain advantages will be more fully apparent from a description of the accompanying drawings, in which:

Figure 1 is a top plan view of the complete insole.

Figure 2 is a bottom view showing a portion of the binding strip drawn back.

Figure 3 is a sectional view taken on line 3—3, Figure 1, showing the details of the structure.

Figure 4 is a sectional view taken transversely through the forepart of a shoe.

Figure 5 is a view of the underside of an insole incorporating a sewing rib or lip and being adaptable to welt-type shoes.

Figure 6 is a sectional view taken on line 6—6, Figure 5, detailing the fabricated structure.

Figure 7 is a view taken similar to Figure 5, but with certain of the parts broken away and thrown back for the purpose of illustrating the entire structure.

Figure 8 is a sectional view taken transversely through the forepart of the shoe of the welt-type, incorporating the improved insole.

Referring to the drawings, the upper of the shoe is indicated at 10, the outsole at 11, and the insole generally at 12. The insole may be applied to any type of shoe construction and in this case, is shown in connection with a McKay shoe. The insole is formed from a blank of leather or other appropriate material in the customary manner, except that it has no forepart, the forepart being constituted by the provision of a resilient pad or cushion 13. This resilient pad or cushion is of the normal outline of the forepart of the insole.

The cushion 13, therefore, extends over the normal area of the forepart of the insole and

presents a soft cushion directly upon the outsole 11 of the shoe and yieldably supporting the metatarsal arch of the foot. The material which has been found best suited to this use and is preferred is a composition made up of cork bonded with latex. However, equivalent compositions may be used. This material, or its equivalent, has the advantage of providing a certain degree of firmness and will not become flattened or permanently distorted because of constant pressure in use.

As stated, these preferred materials do not take stitching well for the stitching has a tendency to tear out of the material. Accordingly, reinforcement for the resilient or cushion material is employed. Toward this end, sheets of material 14, either leather or fabric, are adhesively attached to the resilient pad. These sheets of material are of the same area as the pad. The sheets may be employed only on the top or only on the bottom. It is preferable to use them on both sides in those cases where the insole is to be interchangeable for right or left shoes. The preferred practice is to make up the composition sheets with the layer or layers of reinforcing applied to a blank sheet. The pad sections are then cut to size from the complete sheet.

The forward edge 15 of the heel and shank portion of the insole and the rear edge 16 of the pad portion abut on angular lines. It will be noted that the pad is of greater thickness than the insole, this being done to achieve the proper cushioning action. When the pad is in place (Figure 4) it fills in the concave inner side of the outsole and as stitched affords a raised central area filling in the arch of the forepart of the foot. The parts; that is, the heel and shank portion 17 of the insole and the pad 13, are attached together by means of zigzag stitching 18 applied through a binding or connecting strip 19 overlapping the abutting edges and adhesively applied to the margins of the heel and shank portion 17 and pad 13. Thus, the pad is securely attached to the heel and shank portion and loses none of its natural flexibility. It constitutes a complete flexible insole readily incorporated in the shoe (Figure 4).

As shown in Figure 4, the upper is lasted over the insole as at 20. The outsole is then applied and the parts are secured together by stitching 21. This type of insole is extremely advantageous in that it will not pull apart as the shoe is lasted and the stitching applied to attach the parts together. The reinforcing does not interfere with the natural flexibility of the material and yet provides means whereby the composition will not be pulled or stretched out of shape or caused to pull apart in the operation of pulling the parts over the last in attaching the upper. In other words, the completed insole will not stretch. In the preferred form of the invention, it has been found that a material such as coutil is advantageous. Accordingly, all of the yield or give of the cushion material is vertical; that is, the forepart cannot spread laterally. Particularly, is this so if the layers of covering material are used both on the top and bottom of the cushion pad.

Referring to Figures 5 to 8 inclusive, it will be noted that the basic or fundamental structure is the same as that described heretofore in this specification. A sewing rib or lip 25 is adhesively secured to the margin of the underside of the insole. This rib is formed from a thin strip of

leather material, split at its opposite side edges to provide upturned lips 26 which are joined together adhesively to constitute the attaching lip 27 of the insole. The base portion 28 of this formed rib or lip element, as stated, is adhesively secured to the elements 14 and 17, extending across the connection between the forepart or cushion portion and the heel and shank portion of the insole. This rib extends substantially to the heel portion of the insole.

An additional sheet of material, such as coutil, indicated at 29, is adhesively secured to the bottom of the insole within the area defined by the marginally attached rib. This sheet is extended into contact with the inner face of the rib or lip 27 and is adhesively secured thereto as at 30.

As illustrated in Figure 8, the upper 31 of the modification is lasted over the insole as at 20. Specifically, it is drawn into contact with the outer face of the rib, and the welt strip 32 is stitched into position around the assembled upper and insole by means of stitching 33. The outsole 34 is then applied and is secured to the welt 32 by means of stitching 35. A filler 36 is used between the outsole and the insole to fill in the space defined by the rib. As will be seen, the rib, although not interfering with the flexibility of the insole, tends to further secure the several parts of the insole together against splitting or tearing in use. This will be apparent from the fact that the rib extends across the stitched connection between the cushion portion of the insole and the heel and shank portion of the insole.

Having described my invention, I claim:

1. A fabricated insole, comprising a heel and shank portion, a forepart element of greater thickness than the heel and shank portion and cut to the normal outline of the forepart of the foot, said forepart element formed of cork and latex bonded together, a sheet of substantially nonstretchable material cemented to one of the surfaces of said forepart element, the rear edge of the forepart element and the forward edge of the heel and shank portion abutting, a binding strip overlying the margins of the abutted elements, and stitching through said binding strip extending along and across the abutting edges for attaching the elements firmly together.

2. An improved fabricated insole, comprising a heel and shank portion formed of insole material, a forepart formed of soft yielding composition, said forepart having a reinforcing layer of fabric or the like adhesively attached to one face thereof for reinforcing the composition, the rear edge of the forepart abutting the forward edge of the heel and shank portion and attached thereto by means of stitching, and a reinforcing strip extending along and overlapping the abutting edges.

3. An improved fabricated insole, comprising a heel and shank portion formed of insole material, a forepart formed of soft yielding composition, said forepart having a reinforcing layer of fabric or the like adhesively attached to one face thereof for reinforcing the composition, the rear edge of the forepart abutting the forward edge of the heel and shank portion and attached thereto by means of stitching, a reinforcing strip extending along and overlapping the abutting edges, and a strip, constituting a sewing rib, secured to the margin of the underside of the insole and extending across the abutting edges of

the heel and shank portion and the forepart of the insole.

4. An improved fabricated insole, comprising a heel and shank portion formed of insole material, a forepart cut to the full normal outline of the forward end of the foot and constituting the entire forward end of the insole, said forepart formed of soft yieldable cushion material, said forepart having a reinforcing layer of fabric or the like adhesively attached to one face thereof for reinforcing the material, the rear edge of the forepart abutting the forward edge of the heel and shank portion and attached thereto by means

5 10 of stitching extending through both the layer of fabric and the forepart element and along and parallel with said abutting edges, a strip secured to the margin of the underside of the insole providing an attaching lip, said strip extending around the edge of the shoe and across the abutting edges of the forepart and the heel and shank portion, and a layer of fabric secured to the underside of the insole within the area defined by the strip, said layer of fabric being adhesively secured in position.

MARK L. BROWN.
